UNITED STATES PATENT OFFICE.

NELSON SANFORD STEWART, OF AMSTERDAM, NEW YORK, ASSIGNOR TO STEPHEN SANFORD & SONS, OF SAME PLACE.

DESIGN FOR CARPET.

SPECIFICATION forming part of Design No. 29,429, dated September 27, 1898.

Application filed July 22, 1898. Serial No. 686,686. Term of patent 31 years.

To all whom it may concern:

Be it known that I, NELSON SANFORD STEWART, a citizen of the United States, residing at Amsterdam, in the county of Montgomery and State of New York, have invented and produced a new and original Design for Carpets; and I do hereby declare that the drawing accompanying this specification gives and conveys to any one skilled in the art of carpet-weaving a clear understanding of the same that is sufficient to enable such persons to use my invention.

My invention relates to a design to be worked into or upon carpeting or similar fabrics.

The said drawing is a face view of a carpet embodying my design.

The drawing illustrates a body and a border. The body is in its aspect of ornamentation Persian. The border is also in its aspect of ornamentation Persian.

What I claim, and desire to secure by Letters Patent, is—

1. In a design for carpeting, the body substantially as shown and described.
2. In a design for carpeting, the border substantially as shown and described.
3. The design for carpeting, consisting of the body and the border, substantially as shown and described.

NELSON SANFORD STEWART.
